[57] CLAIM

The ornamental design for a cover for the motor of a ceiling fan, as shown and described.

DESCRIPTION

FIG. 1 is a side elevational view of a cover for the motor of a ceiling fan, showing my new design, the other sides being identical to that shown;

FIG. 2 is a top plan view thereof;

FIG. 3 is a bottom plan view thereof;

FIG. 4 is a side elevational view of a second embodiment thereof, the other sides being identical to that shown;

FIG. 5 is a top plan view of the embodiment of FIG. 4; and,

FIG. 6 is a bottom plan view of the embodiment of FIG. 4.

FIG. 2

FIG. 1

FIG. 3

FIG. 5

FIG. 4

FIG. 6
